US00D857712S

(12) **United States Design Patent** (10) **Patent No.:** **US D857,712 S**
Grecia (45) **Date of Patent:** **** Aug. 27, 2019**

(54) **DISPLAY SCREEN OR PORTION THEREOF
WITH A GRAPHICAL USER INTERFACE**

(71) Applicant: **Qondado LLC**, San Juan, PR (US)

(72) Inventor: **William Grecia**, Downingtown, PA (US)

(73) Assignee: **QONDADO LLC**, San Juan, PR (US)

(**) Term: **15 Years**

(21) Appl. No.: **29/671,357**

(22) Filed: **Nov. 27, 2018**

CLAIM

The ornamental design for a display screen or portion thereof with a graphical user interface, as shown and described.

DESCRIPTION

The sole FIGURE is a front view of a display screen or portion thereof with a graphical user interface showing my design.

The outermost broken lines show a display screen or portion thereof and form no part of the claimed design.

1 Claim, 1 Drawing Sheet
